BEARING FOR VACUUM TUBE WORK

Sanford F. Essig, Fort Wayne, Ind., assignor to
Farnsworth Television and Radio Corporation,
a corporation of Delaware

Application May 14, 1945, Serial No. 593,747

5 Claims. (Cl. 308—241)

1

This invention relates generally to electrode supports for vacuum tubes, and more particularly relates to devices for movably supporting electrodes in glass supports.

It is frequently desirable to supply mechanical motion to certain electrodes of a vacuum tube. Thus, an unbalanced wheel may be turned by the action of gravity or a magnetic armature may be rotated by an external magnetic field thereby to move an electrode. In this manner it is possible to exchange, for example, in a cathode ray tube, one electrode having a large aperture for another electrode having a small aperture in order to vary the cross-sectional area of an electron beam. In certain types of X-ray tubes it is necessary to rotate the anode in order to present a different area to the electron beam to prevent over-heating of the anode. It may also be desired to change the electron emission of a cathode in a vacuum tube or similar device by moving a shield in front of the cathode to obscure a larger or smaller portion of the electron beam.

It is conventional practice to provide most types of vacuum tubes with a glass envelope. Thus, the problem arises of movably mounting an electrode support which usually consists of metal in the glass envelope of a vacuum tube. However, as is well known, glass wets metals and, therefore, forms a bond with the metal. Hence, it is very desirable to provide apparatus for movably supporting a metallic electrode in a glass envelope.

It is an object of the present invention, therefore, to provide a novel, movable electrode support suitable for use in vacuum tubes and a method of manufacturing the same.

A further object of the invention is to provide a bearing adapted to be mounted in a glass support.

In accordance with the present invention, there is provided apparatus for movably supporting an electrode in an evacuated vessel comprising a glass envelope, a metallic electrode support, a coating of lubricant film on a portion of the electrode support and a metallic sleeve in intimate contact with the lubricant film and a portion of the glass envelope.

For a better understanding of the invention, together with other and further objects thereof, reference is made to the following description, taken in connection with the accompanying drawing, and its scope will be pointed out in the appended claims.

In the accompanying drawing, Fig. 1 is a sectional view of two bearings embodying the present invention and mounted in a glass envelope, while

2

Fig. 2 is a sectional view on enlarged scale of one of the bearings of Fig. 1 without its glass support.

Referring now more particularly to Fig. 1 of the drawing, there is illustrated a fragmentary portion of glass envelope 1 having two glass projections 2 and 3 forming a support for bearings 4 and 5, respectively. Metallic rod or wire 6 is provided with circular grooves 7 and 8 at both ends thereof. Disk 10 carried by metallic rod 6 is shown by way of illustration and may be used for securing thereto the elements such, for example, as electrodes which it is desired to rotate.

Bearing 5 without its glass support 3 is shown on enlarged scale in Fig. 2. In accordance with the present invention, the free end portion of rod 6 is coated with a film 11 of a suitable lubricant of low vapor pressure such, for example, as graphite or certain metals including silver or barium. Preferably, film 11 consists of graphite which is a good lubricant and has a low vapor pressure. Graphite film 11 may be applied as an aqueous suspension of graphite such as Aquadag. The aqueous graphite suspension may then be dried, for instance, by heating rod 6, to form graphite film 11.

Since glass can not be made to wet graphite film 11, it may be coated with a metal to form a tight fitting sleeve 12, the coating being preferably effected by plating graphite film 11 with a metal. The metal of which sleeve 12 consists should have the same thermal coefficient of expansion as glass support 3. Thus, when glass supports 2 and 3 consist of lead glass or lime glass, that is of soft glass, metallic sleeve 12 may, for instance, be made of platinum or Domet which is a copper-clad nickel-copper alloy. The thermal coefficient of expansion of tungsten matches that of Pyrex as well as Nonex which are both hard glasses. Kovar or Fernico and similar iron-alloy metals may be used in connection with a special seal glass sold in the trade under the name of 7052 glass.

After graphite film 11 has been plated with metal to form sleeve or film 12, both metallic sleeve 12 and its glass support such as 3 are heated until the glass wets metallic sleeve 12. Now metallic sleeve 12 is embedded in hot glass support 3. After glass support 3 and metallic sleeve 12 have cooled the glass forms a bond with metallic sleeve 12. Metallic rod 6 will now turn freely in its metallic sleeve 12, while graphite film 11 acts as a lubricant. Circular grooves 7 and 8, which preferably are provided in rod 6, prevent rod 6 from moving axially in its bearings. It is also feasible to coat only circular grooves 7 and

8 with graphite film 11 and metallic sleeve 12 in which case grooves 7 and 8 provide the actual bearing. Bearing 4 may be manufactured in the same manner as bearing 5.

A bearing of the type described will operate as well in a high vacuum as under atmospheric pressure. Lubricant film 11 preferably consists of graphite which has a very low vapor pressure and thus can not contaminate the vacuum tube. If graphite film 11 would be embedded directly in glass, the glass would not wet the graphite and hence a close fit could not be obtained.

While there has been described what is at present considered the preferred embodiment of the invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. Apparatus for movably supporting an electrode in an evacuated vessel comprising a glass envelope, a metallic electrode support, a coating of lubricant film on a portion of said support, and a metallic sleeve in intimate contact with said film and a portion of said glass envelope.

2. Apparatus for movably supporting an electrode in an evacuated vessel comprising a glass envelope, a metallic electrode support having a portion provided with a circular groove, a coating of graphite film on said portion and said groove, and a metallic sleeve in intimate contact with said film and a portion of said glass envelope.

3. Apparatus for movably supporting an electrode in an evacuated vessel comprising a glass envelope, a metallic electrode support, a coating of graphite film on a portion of said support, and

5 a metallic sleeve in intimate contact with said film and a portion of said glass envelope, said metallic sleeve and said glass envelope being chosen to have substantially the same thermal coefficient of expansion.

4. Apparatus for movably supporting an electrode in an evacuated vessel comprising a glass envelope, a metallic electrode support having an end portion provided with a circular groove, a coating of graphite film on said groove, and a metallic film in intimate contact with said graphite film and a portion of said glass envelope, said metallic film and said glass envelope being chosen to have substantially the same thermal coefficient of expansion.

5. The method of movably supporting a metallic electrode support in an evacuated glass envelope which comprises the steps of coating a portion of said support with an aqueous suspension of graphite to form a graphite film, selecting a metal having the same thermal coefficient of expansion as said glass envelope, plating said graphite film with said selected metal to form a metallic sleeve, heating said metallic sleeve and a portion of said glass envelope until said glass wets said metallic sleeve, and embedding said metallic sleeve in said portion of said glass envelope to form a bond therewith.
